UNITED STATES PATENT OFFICE.

GEORGE D. POTTER, OF SPOKANE, WASHINGTON.

EJECTING MECHANISM FOR BREAKDOWN GUNS.

SPECIFICATION forming part of Letters Patent No. 625,601, dated May 23, 1899.

Application filed August 31, 1898. Serial No. 689,911. (No model.)

To all whom it may concern:

Be it known that I, GEORGE D. POTTER, a citizen of the United States, residing at Spokane, in the county of Spokane and State of Washington, have invented a certain new and useful Improvement in Breakdown Firearms; of which the following is a full, clear, and exact description.

This invention relates more especially to a breech-loading hammerless breakdown shotgun, and the object of the invention is to provide a simple and effective ejector mechanism.

In carrying out my invention I use an ejector mechanism in conjunction with an extractor and in such manner that the extractor and ejector may both be used or the extractor alone employed.

The extractor may be of any approved construction, and combined therewith is an ejector-hammer under the control of a spring and having a plunger which is brought into operative connection with the extractor-stem in certain conditions of the barrel, all as I will proceed now more particularly to set forth and finally claim.

In the accompanying drawings, illustrating my invention, in the several figures of which like parts are similarly designated, Figure 1 is a longitudinal section of sufficient of a double-barrel shotgun to illustrate one form of my invention, the section being taken to show the left-hand-barrel mechanism and the parts being in position after firing and before the barrels are dropped to open the gun. Fig. 2 is a view similar to Fig. 1, but omitting the lock mechanism and with the barrels dropped, the extractor partly projected, and the ejector-hammer at full-cock and on the point of release from the cocking-lever. Fig. 3 is a view similar to Fig. 2 with the ejector mechanism in position after action, the extractor fully projected, and the ejector-plunger lying below the low extractor-stem and in position where the gun may be closed for firing. Fig. 4 is a bottom plan view of the ejector mechanism. Fig. 5 is an edge view and a side elevation of one of the ejector hammers and plungers. Fig. 6 is a side view and an edge view of the stirrup. Fig. 7 is a section of the tension-lever and spring-hanger. Fig. 8 is a view similar to Fig. 1, but omitting the lock mech-

anism and showing the tension-lever of the ejector mechanism reversed in order to throw the ejector mechanism out of operation and to enable the gun to be used with the extractor and without the ejector. Fig. 9 is a view similar to Fig. 8, with the fore-end in the first position of mounting, the end of the tension-lever bearing against the bottom rib of the barrels, the spring relaxed, and the trip of the ejector-hammer out of the way of the cocking-lever while mounting.

a is a part of the stock; *a'*, the standing breech or break-off; *a²*, the barrel-locking lever; *a³*, an ordinary firing-pin; *a⁴*, a tumbler or hammer; *a⁵*, a mainspring; *a⁶*, a stirrup pivoted to the hammer and connected with the mainspring; *a⁷*, a sear coöperating in any usual manner with the bends of the tumbler, and *a⁸* a cocking-rod. *b* is a cocking-lever journaled in the hinge-pin *b'* and having a notch or hook *b²* projecting through the slot *b³* in the fore-end. *c* is the stationary positive extractor-post, and *c'* the extractor-stem, having in it the notch *c²*, with which the extractor-post coöperates, and provided with any usual extractor-head. All these several parts may be of substantially the construction covered by my Patent No. 542,494, granted July 9, 1895.

It will be understood, of course, that the mechanism for one barrel only need be described, inasmuch as it is duplicated for the other barrel.

In the present invention I employ an ejector-hammer *d*, having a hub *d'*, which receives the pivot-pin *d²*. As shown more especially in Figs. 4 and 5, this ejector-hammer has a blade *d³* projecting from its hub, and in this blade is fulcrumed the ejector-plunger *e*, the said plunger having a sort of knuckle-joint *e'* with the blade *d³* and being normally projected from the said blade by means of any suitable spring or combination of springs *e²*.

f is a stirrup pivoted in a recess *f'* in the hub *d'* and having a slight vibratory motion. This stirrup has at its upper end the cross-head *f²*. The hub *d'* is extended rearwardly and provided with a trip or hook *h* for coöperation with the hook *b²* of the cocking-lever.

i is a spring one end of which is forked to engage the cross-head *f²* of the stirrup, the

other end of which may be secured in the fore-end iron *j*. The springs for the two barrels are supported in a hanger *k*, and this hanger has applied to it a piston *l*, the said 5 piston being screwed into the hanger in order to adjust its effective length. This screw-piston extends through a hole in the fore-end iron and has pivoted to it the tension-lever *m*, which is arranged between the bottom of 10 the barrels and the top of the fore-end iron. A spring *n* surrounds the piston *l* between the fore-end iron and the spring-hanger and serves to throw down the ejector-spring *i* and hold the ejector mechanism out of play, as 15 illustrated in Fig. 9, while the parts are being assembled. The tension-lever *m* lies partly in a depression *m'* in the fore-end iron *j* and between the bottom rib of the barrels and the fore-end iron when the latter is in position. 20 Said lever *m* preferably is of approximate rhombohedral form, with one corner *m*² rounded off and the angles of all of the corners taken off circularly. A kerf *m*³, Fig. 7, is made in one end, and in this kerf is pivoted 25 the piston *l*, thereby forming a fulcral point upon which the lever *m* turns against or upon the fore-end iron.

When the gun is assembled as in Fig. 1, with the tension-lever extending toward the 30 muzzle of the barrels and the gun is fired, the cocking-rod, acting upon the cocking-lever *b*, throws the said lever forward and upward and causes its notch *b*² to engage the hook *h* of the hub of the ejector-hammer, 35 whereby the two are held in engagement. As the barrels are dropped to open the gun, as in Fig. 2, the cocking-lever is withdrawn back into the slot in the fore-end by reason of its eccentric bearing in the hinge-pin *b'*, 40 and consequently serves to revolve the ejector-hammer, by reason of its engagement with the hub *d'* thereof, and brings said ejector-hammer into the cocked position illustrated in Fig. 2. When said ejector-hammer has 45 been revolved to its cocked position, just described, the extractor-stem *c'*, actuated by the positive (stationary) extractor-post *c*, has been moved rearwardly about one-half of its total throw, and the plunger *e* is thrown up 50 by its spring into engagement with a second notch *o* in the extractor-stem, and the hooks on the cocking-lever and the hub of the ejector-hammer are fully disengaged, and the ejector-hammer is revolved backwardly under the impulse of the ejector-spring *i*, which 55 motion being transmitted to the plunger effects a sudden movement of the extractor, completes the throw thereof, and ejects the partly-extracted shell from the barrel. As 60 the ejector-hammer revolves backwardly, as just described, the front edge of the notch *o*, bearing down upon the plunger, gradually expels the said plunger from said notch, and at the completion of the throw of the ejector 65 said plunger is fully expelled from said notch and lies under and out of the channel of the extractor-stem, as shown in Fig. 3. If now

the barrels be closed, the extractor strikes against the standing breech and is driven back into its original position, as in Fig. 1, 70 and the plunger offers no resistance to such motion, and it will be observed as a peculiarity of my mechanism that the plunger *e* and the notch *o* in the extractor-stem only come into engagement when the said plunger 75 and said extractor-stem are simultaneously moved in opposite directions. The gun having been cocked by the dropping of the cocking mechanism upon the cocking-lever, the latter drops to the dotted position, Fig. 1, and 80 when in this position and until the gun has been fired or the tumbler or hammer lowered the said cocking-lever does not engage with or act upon the hub of the ejector-hammer when the gun is opened and closed, and therefore the ejector mechanism is inoperative, 85 but the positive extractor operates in the usual manner.

The tension-lever *m* is so shaped that it automatically stands in the position shown in 90 Fig. 9 when the fore-end is detached from the barrels. When ready to assemble the parts as an ejector-gun, the said lever *m*, standing up, as shown in Fig. 9, allows the springs *i* to fall into a relaxed position and the ejector-hammer to revolve forward with its hook out of the way of the cocking-lever. In this position the fore-end may be attached with the tumblers or hammers of the gun down and the cocking-levers thrown up. 100 When the fore-end, placed in this position, is pressed up against the barrels, the lever *m* is forced down upon the fore-end iron, as shown in Fig. 1, and its fulcrum-point bearing upon said fore-end iron raises the piston *l* and its 105 attached spring-hanger and springs, and thereby puts said springs under tension and brings the ejector-hammers into position. (Shown in Fig. 1.) It will be observed that the lever *m* by this arrangement admits of the fore-end 110 being mounted when the tumblers or hammers are down and automatically puts the ejector-springs under tension.

When it is desired to use the gun as a non-ejector-gun, the tension-lever *m* may be 115 turned down backward upon the fore-end iron, as illustrated in Fig. 8, and when the fore-end is then mounted under the barrels the ejector mechanism remains out of engagement with and is not acted upon by the cocking-lever, but the positive extractor still performs its function.

For a further and detailed description of the cocking-lever reference is made to my patent hereinbefore referred to.

It will be seen that the plungers operate in vertical slots in the fore-end iron and that the cross-heads of the stirrups *f* strike the under side of the fore-end iron in the upward movement of the ejector-hammers, and thereby limit the throw of the said stirrups and the attached hammers and springs, thereby preventing the hook *h* of the hub *d'* and the hook *b*² of the cocking-lever *b* from striking

together, the cross-head of the stirrups striking the fore-end iron on one side of the slots in same.

What I claim is—

- 5 1. In a breech-loading breakdown gun, a fore-end iron, a lever applied to such fore-end iron, an ejector-spring and mechanism connecting the lever and spring whereby said spring is put under tension when the fore-end is pressed into position on the barrels.
- 10 2. In a breech-loading breakdown gun, an ejector, a fore-end iron, a reversible lever on such fore-end iron, an ejector-spring and mechanism connecting said lever and spring, whereby when said lever stands in one position, said spring is put under tension and when in another position said spring and ejector are held out of play when the fore-end is placed in position on the barrels.
- 15 3. In a breech-loading breakdown gun, a fore-end iron, an extractor having a notched stem, and an ejector-hammer pivoted in the fore-end and having a spring-pressed plunger jointed thereto and adapted to rise and engage with the notch in the extractor-stem when said ejector-hammer is cocked, and by said notch to be tripped and disengaged from said extractor-stem when the ejector-hammer falls.
- 20 4. In a breech-loading breakdown gun, the combination with the fore-end iron, of a tension-lever, mounted upon the said fore-end iron, a piston pivoted to said lever, a spring, and a spring-hanger adjustably attached to the lower end of said piston, substantially as and for the purpose described.
- 25 5. In a breech-loading breakdown gun, the combination with the fore-end iron, of a tension-lever mounted on the fore-end iron and adapted to be depressed by contact with the

bottom rib of the barrels when the fore-end is mounted thereon.

6. In a breech-loading breakdown gun, the combination with the fore-end iron, and an ejector-hammer, of a tension-lever, spring-hanger and spring, connected to hold the ejector-hammer retracted and clear of the cocking-levers until the fore-end is placed in position. 45

7. In a breech-loading breakdown gun, the combination of a tension-lever, a plunger and a spring-hanger, with an ejector-spring, an ejector-hammer and a connecting-stirrup, substantially as described. 50

8. In a breech-loading breakdown gun, the combination of a tension-lever, a piston, a coiled spring surrounding said piston and a spring-hanger, substantially as described. 55

9. In a breech-loading breakdown gun, the combination of a tension-lever, a piston, a coiled spring surrounding said piston and a spring-hanger with an ejector-spring, an ejector-hammer having a jointed plunger and a connecting-stirrup, substantially as and for the purpose described. 60 65

10. In a breech-loading breakdown gun, the combination of an ejector-hammer, an ejector-spring and a stirrup attached to said spring and pivoted to the ejector-hammer, the upper end of said stirrup being adapted to strike the under side of the fore-end iron and so limit the throw of said stirrup and attached hammer and spring. 70 75

In testimony whereof I have hereunto set my hand this 23d day of August, A. D. 1898. 75

GEORGE D. POTTER.
